DWIGHT W. WADSWORTH, OF FENNVILLE, MICHIGAN

PACKING APPARATUS

Application filed November 9, 1929. Serial No. 405,902.

In the packing of fruits and vegetables, it is quite common practice to provide a packing receptacle or device which permits the desired arrangement of a facing, place a basket or 5 container over the packing device in inverted position and then reverse the receptacle so that the facing is properly presented on the receptacle.

The main objects of this invention are:

10 First, to provide an apparatus by means of which receptacles, such as bushel baskets, may be quickly reversed with a minimum of effort on the part of the operator.

Second, to provide an apparatus of this 15 character in which the receptacle is automatically secured to the reversing table merely by the act of placing the receptacle in inverted position upon the table, the weight of the receptacle acting to lock the receptacle to the 20 holder during the reversing movement.

Third, to provide an apparatus of this character in which the receptacle is automatically discharged from the reversing table without disturbing the contents thereof.

25 Objects relating to details and economies of my invention will appear from the description to follow. The invention is defined and pointed out in the claims.

A structure which is a preferred embodiment of my invention is illustrated in the accompanying drawing, in which:

Fig. 1 is a rear perspective view of an apparatus embodying the features of my invention with a receptacle mounted on the table.

35 Fig. 2 is a fragmentary side elevation with the parts in position shown in Fig. 1.

Fig. 3 is a side elevation with the table in reversed position, successive positions of the receptacle as discharged being indicated by 40 dotted lines.

Fig. 4 is a fragmentary view looking from the right of Fig. 2.

45 Fig. 5 is a fragmentary front elevation showing details of the discharge conveyor.

Fig. 6 is a detail view illustrating the relation of the receptacle holders to the receptacle and the action of the receptacle in moving the holder to engaging position, the holder 50 being shown in open position by full lines

and in closed or receptacle engaging position by dotted lines.

Fig. 7 is a fragmentary plan view of the parts shown in Fig. 6.

In the embodiment of my improvements illustrated, I provide a pair of base members 1 having uprights 2 mounted thereon. These uprights are connected at their lower ends by means of the cross piece 3 and at an intermediate point by means of the cross piece 4, this cross piece being mounted on the uprights for vertical adjustment, it having sleeves 5 at its ends slidable on the uprights and held in adjusted position by means of the screws 6. The table supporting brackets 7, 55 preferably in the form of castings, are mounted on the upper ends, these supports having collars or sleeves 8 and 9 vertically adjustable on the uprights and secured in adjusted position by the set screws 10. These brackets 60 have vertically elongated bearings 11 and keepers 12 and 13, the keepers having forwardly and downwardly inclined guides 14 and 15 respectively, the purpose of which will appear as the description proceeds. 65

The table 16 is of a size and character to receive a receptacle 17, the structure illustrated being designed to handle bushel baskets, and the facing member 18.

The table is reversibly supported by the arm-like hangers 19 having journals 20 engaging the bearings 11 in the supporting brackets.

The table is provided with stud-like detents or latches 21 provided with rollers adapted 75 to engage with the roller 12 when the table is in its upright position shown in Fig. 1 or with the keeper 13 when the table is in its reversed position as shown in Fig. 3, the detents traveling up the inclined guides 14 and 15 as the table is swung from one position to another, dropping into the detents when the table is in completely reversed position or in its initial upright position. A slight upward lift of the table frees the dents from 80 the keepers.

At the rear of the table is an angled post 22, this post being mounted for longitudinal adjustment in the bracket 23 with its arm 24 in overhanging relation to the receptacle. This 85

arm carries a pivot 25 for the angled holder members 26, the arms 27 of these holders being adapted to engage the bottom of the receptacle while the arms 28 are adapted to engage the rear edge thereof so that as the receptacle is pushed rearwardly on the table it engages the arms 28 as shown in Fig. 6, carrying the arms 27 downwardly on the receptacle and as the table is reversed, the weight of the receptacle tends to urge the holder to holding or clamping position. As soon, however, as the table is reversed, the holder permits the receptacle to drop onto the way members 29 which are disposed in spaced relation with their forward ends below the table and between the uprights.

These way members 29 are provided with a plurality of rollers 30 so that the receptacle travels down the same by gravity and onto a suitable conveyor, not illustrated.

To ease the receptacle onto the discharge way, I provide a pair of transfer arms 31 which are pivoted on the cross piece 3 to project upwardly between the way members. A coiled spring 32 acts to hold these arms in their forward or receiving position as shown in Fig. 3, the arms swinging down as the receptacle is discharged from the holders as indicated by dotted lines in Fig. 3.

The holders serve as slides for the receptacle, see Fig. 3, so that it is automatically discharged upon the way when the table is reversed.

The holders are yieldingly held against the stops 33 by means of the springs 34 so that they do not interfere with the operator placing the receptacle upon the table but, as stated, when the receptacle engages the arms 28 of the holders they are swung down into operative engagement with the receptacle and as the table is reversed the weight of the receptacle holds them in engagement.

The table is so balanced with a filled receptacle thereon, as shown in Figs. 1 and 2, that the greatest weight is at the rear so that a slight upward pull on the front end of the table disengages the detent from the keeper 12 and the table automatically swings to reversed position with the detent in engagement with the keeper 13. As soon as the receptacle is discharged a forward pull on the table returns it to upright position.

I have illustrated and described my improvements in an embodiment which has proven highly practical. I have not attempted to illustrate and describe various modifications and adaptations which I contemplate as it is believed that this disclosure will enable those skilled in the art to embody or adapt the same as may be desired.

Having thus described my invention, what I claim as new and desire to secure by Letters Patent, is:

1. In an apparatus of the class described, the combination of a support comprising

spaced uprights, a pair of supporting brackets having vertically elongated bearings therein and forwardly facing keepers above and below said bearings, said keepers being provided with downwardly inclined guides, a table provided with hangers journaled in said bearings in said supporting brackets and provided with detents adapted to engage with the lower keepers when the table is in inverted position, an angled post mounted for longitudinal adjustment on the rear end of said table in overhanging relation to a receptacle on the table, a receptacle holder pivotally mounted on said post and having arms on opposite sides of its pivot disposed at an angle to each other, one arm being adapted to engage the bottom of a receptacle and the other an edge thereof, spaced rearwardly inclined way members disposed with their front ends below said table to receive the receptacle discharged therefrom, transfer arms pivotally mounted at their lower ends on said support to project upwardly and rearwardly between said way members, and a spring acting to yieldingly hold said transfer arms in retracted position with their upper ends projecting above the plane of said way members and positioned to receive a receptacle discharged from said table.

2. In an apparatus of the class described, the combination of a support comprising spaced uprights, a pair of supporting brackets having vertically elongated bearings therein and forwardly facing keepers above and below said bearings, said keepers being provided with downwardly inclined guides, a table provided with hangers journaled in said bearings in said supporting brackets and provided with detents adapted to engage with the lower keepers when the table is in upright position and with the upper keepers when the table is in inverted position, an angled post mounted for longitudinal adjustment on the rear end of said table in overhanging relation to a receptacle on the table, a receptacle holder pivotally mounted on said post and having arms on opposite sides of its pivot disposed at an angle to each other, one arm being adapted to engage the bottom of a receptacle and the other an edge thereof, and a rearwardly inclined way disposed with its front ends below said table to receive the receptacle discharged therefrom.

3. In an apparatus of the class described, the combination of a support comprising spaced uprights, a pair of supporting brackets having vertically elongated bearings therein and forwardly facing keepers above and below said bearings, said keepers being provided with downwardly inclined guides, a table provided with hangers journaled in said bearings in said supporting brackets and provided with detents adapted to engage with the lower keepers when the table is in upright position and with the up-

per keepers when the table is in inverted position, a pivotally mounted angled holder on said table having a part projecting forwardly from its pivot when the table is in upright position to engage the bottom of a receptacle and a part projecting rearwardly from its pivot to engage a rear portion of the receptacle, a rearwardly inclined way disposed below said table to receive the receptacle discharged therefrom, a transfer arm pivotally mounted at its lower end, and a spring acting to yieldingly hold said transfer arm in retracted position with its upper end projecting above the plane of said way and positioned to receive a receptacle discharged from said table.

4. In an apparatus of the class described, the combination of a support comprising spaced uprights, a pair of supporting brackets having vertically elongated bearings therein and forwardly facing keepers above and below said bearings, said keepers being provided with downwardly inclined guides, a table provided with hangers journaled in said bearings in said supporting brackets and provided with detents adapted to engage with the lower keepers when the table is in upright position and with the upper keepers when the table is in inverted position, and a pivotally mounted angled holder on said table having a part projecting forwardly from its pivot when the table is in upright position to engage the bottom of a receptacle and a part projecting rearwardly from its pivot to engage a rear portion of the receptacle.

5. In an apparatus of the class described, the combination of a pair of supporting brackets having vertically elongated bearings and forwardly facing keepers above and below said bearings, said keepers being provided with downwardly inclined guides, a table provided with hangers journaled in said bearings in said supporting brackets and provided with detents engageable with said keepers when the table is in upright and inverted positions, a holder mounted on said table to engage a receptacle arranged thereon and automatically actuated to clamping position by the weight of the receptacle during the reversing movement of the table, and a support to which the receptacle is automatically discharged when the table is swung to inverted position.

6. In an apparatus of the class described, the combination of a pair of supporting brackets having bearings and forwardly facing keepers above and below said bearings, a table provided with hangers journaled in said bearings in said supporting brackets and provided with detents engageable with said keepers when the table is in upright and inverted positions, and automatically engaging and releasing means for holding a re-

ceptacle during the reversing movement of the table.

7. In an apparatus of the class described, the combination of a pair of supporting brackets having bearings and forwardly facing keepers above and below said bearings, a table provided with hangers journaled in said bearings in said supporting brackets and provided with detents engageable with said keepers when the table is in upright and inverted positions, and means for holding a receptacle during the reversing movement of the table.

8. In an apparatus of the class described, the combination of a support, a table provided with hangers journaled on said support for rotative and vertical movement, said support being provided with keepers above and below the journal, the table being provided with detents engageable with and disengageable from said keepers with a combined vertical and rotative movement of the table, and a receptacle holder mounted on said table to be automatically engaged by a rearward movement of the receptacle on the table and automatically released by a forward movement of the receptacle relative to the table.

9. In an apparatus of the class described, the combination of a support, and a table provided with hangers journaled on said support for rotative and vertical movement, said support being provided with keepers above and below the journal, the table being provided with detents engageable with and disengageable from said keepers with a combined vertical and rotative movement of the table.

10. In an apparatus of the class described, the combination of a support, a table provided with hangers journaled on said support, coacting keepers and detents on said table and support adapted to releasably hold the table in its upright and reversed positions, and a receptacle holder pivotally mounted on the rear of the table and adapted to engage the bottom and a rear part thereof so that as the table is swung from upright to reversed position the weight of the receptacle acts to hold said holder in engagement with the receptacle and the holder is automatically released when the table is in inverted position.

11. In the apparatus of the class described, the combination of a support, a table provided with hangers journaled on said support, and a receptacle holder pivotally mounted on the rear of the table and adapted to engage the bottom and a rear part thereof so that as the table is swung from upright to reversed position the weight of the receptacle acts to hold said holder in engagement with the receptacle and the holder is automatically released when the table is in inverted position.

12. In an apparatus of the class described, the combination of a support, a table provid-

ed with hangers journaled on said support, coacting keepers and detents on said table and support adapted to releasably hold the table in its upright and reversed positions, and a receptacle holder on said table.

5 13. In an apparatus of the class described, the combination of a reversably mounted table, automatically engaging means for releasably supporting said table in its upright 10 and reversed positions, and a receptacle holder carried by said table and adapted to be held in engagement with the receptacle during the reversing of the table by the weight of the receptacle.

15 14. In an apparatus of the class described, the combination of a reversably mounted table, an angled post mounted at the rear end of the table in overhanging relation to a receptacle on the table, and a receptacle holder 20 pivotally mounted on said post and having arms on opposite sides of its pivot disposed at an angle to each other, one arm being adapted to engage the bottom of a receptacle and the other an edge thereof.

25 15. In an apparatus of the class described, the combination of a reversably mounted table, and a pivotally mounted receptacle holder carried by said table and having arms on opposite sides of its pivot disposed at an 30 angle to each other, one arm being adapted to engage the bottom of a receptacle and the other an edge thereof.

35 16. In an apparatus of the class described, the combination of a reversably mounted table, and a pivotally mounted holder on 40 said table having a part projecting forwardly from its pivot when the table is in upright position to engage the bottom of a receptacle and a part projecting rearwardly from its pivot to engage a rear portion of the receptacle.

45 17. In an apparatus of the class described, the combination of a reversably mounted table, and a pivotally mounted receptacle holder carried by the table and having parts engaging the sides and bottom of the receptacle so that the load on the parts engaging the sides of the receptacle as the table is reversed acts to urge the part engaging the 50 bottom of the receptacle against the receptacle.

55 18. In an apparatus of the class described, the combination of a reversably mounted table, and a receptacle holder carried by the 60 table and arranged to engage a side and bottom thereof so that pressure on the part engaging the side of the receptacle urges the part engaging the bottom of the receptacle against the receptacle during the reversing of the table.

65 19. In an apparatus of the class described, the combination of a reversably mounted table, and a receptacle holder pivotally mounted on said table and provided with an arm engaging the rear side of the recep-

70 tacle and an arm engaging the bottom thereof, the arm engaging the bottom being actuated to receptacle-engaging position by pressure on the arm engaging the side of the receptacle so that the holder is automatically engaged by a rearward movement of the receptacle on the table and automatically released by a forward movement of the receptacle relative to the table.

75 In witness whereof I have hereunto set my hand.

DWIGHT W. WADSWORTH.
